[57] CLAIM

The ornamental design for a combined transmitter and receiver for locating children, as shown and described.

DESCRIPTION

FIG. 1 is a perspective view of a combined transmitter and receiver for locating children showing my new design;

FIG. 2 is a front elevational view thereof, of the transmitter portion;

FIG. 3 is a rear elevational view thereof;

FIG. 4 is a right side elevational view thereof;

FIG. 5 is a left side elevational view thereof;

FIG. 6 is an end elevational view thereof;

FIG. 7 is an end elevational view thereof, from the opposite end;

FIG. 8 is a front elevational view thereof, of the receiver portion;

FIG. 9 is a rear elevational view thereof;

FIG. 10 is a right side elevational view thereof;

FIG. 11 is a left side elevational view thereof;

FIG. 12 is an end elevational view thereof; and,

FIG. 13 is an elevational view thereof, from the opposite end.
